UNITED STATES PATENT OFFICE.

ROBERT CUMMING ANNAND, OF SOUTH SHIELDS, ENGLAND.

FLAT-BED PRINTING-MACHINE.

1,262,616.

Specification of Letters Patent. Patented Apr. 16, 1918.

Application filed August 20, 1915. Serial No. 46,489.

To all whom it may concern:

Be it known that I, ROBERT CUMMING ANNAND, of South Shields, in the county of Durham, England, a subject of the King of 5 Great Britain, have invented certain new and useful Improvements Relating to Flat-Bed Printing-Machines, of which the following is a specification.

This invention relates to flat bed printing 10 and perfecting machines of the kind in which the flat type beds and the impression cylinders are mounted in reciprocating relation with each other and in which the impression cylinders for printing the respective sides of the paper in coöperation with 15 their type beds are alternately lowered and raised into and out of the plane of printing contact with their respective forms, in such manner that when one cylinder is lowered 20 and printing one side in one direction of stroke, the other is raised clear of its form, and in the other direction of stroke the second cylinder is lowered and prints the opposite side in contact with its form while 25 the former cylinder is raised, means being provided to transfer the partly printed sheet from the first cylinder to the second, and the cylinders being provided with grippers operated to receive and release the 30 sheets at the required times.

The invention has for object to provide improvements in sheet perfecting machines of the class referred to and in particular in such machines wherein the impression cylinders reciprocate over the bed.

According to the first improvement, two impression cylinders alternately and inversely lowered and raised into and out of printing relation to the type beds and rotated both in the same directions by racks carried by the type beds, are spaced apart in combination with sheet transferring mechanism between them, arranged to convey the partly printed sheet from the lower 45 part of the first impression cylinder to the top or approximately the top of the second impression cylinder to be seized by the grippers of the latter. In carrying out this improvement I make the spacing of the cylinders such that the sheet or the full-sized sheet when the machine is constructed to print variable sized sheets,—after being printed on one side by the first impression cylinder, reaches from the lower side of this 50 cylinder to about the top of the second impression cylinder.

The invention further comprises in com-

bination with rising and falling impression cylinders and their intermediate sheet transferring mechanism arranged and operating 60 as described and to reciprocate over the type beds, and with eccentric bearings or disks in which the cylinders are mounted and having arms for turning them to raise the cylinders, of levers operated by eccentric devices 65 which partly revolve the eccentric bearings of the cylinders during the last inch or so of travel and during the stationary interval at the ends of the stroke and during the first inch or so of travel in the reverse direction.

In combination with this arrangement I also propose to employ a tappet device or devices located in an intermediate position to act on the arms of the eccentric bearings 75 of the cylinders, for lowering the cylinders to the printing plane.

Preferably the impression cylinders remain in continuous gear with the racks that revolve them.

Further according to the invention the sheet conveying mechanism between the cylinders and serving to convey the partly printed sheet head foremost from the first cylinder to grippers at about the top of the 85 second cylinder as before mentioned is combined with means whereby the rollers of this sheet conveying mechanism are made to revolve in one direction only and at the surface speed of the cylinders, while the cylinders revolve in both directions as the result of their meshing with their driving racks in the reciprocation.

For this purpose I may according to the invention employ an arrangement of free 95 wheel apparatus adapted through the medium of a ratchet wheel and oppositely driving pawls, or other suitable mechanism, to transmit the reciprocating motion of the cylinder carriage or support as a drive in 100 a constant direction to the sheet conveying mechanism.

Further according to the invention I arrange the form inking rollers on the outer sides of and to reciprocate with the impression cylinders and sheet transferring mechanism before described, in combination with ink supply ducts and distributing rollers arranged at each end of the machine for the respective forms, the distributing rollers being disposed in a horizontal plane and the two sets of distributing rollers being so spaced apart that when the form inking rollers are moving at the respective end por-

tions of their travel they pass backward and forward over the distributing rollers and receive ink from them.

In combination with such an arrangement I preferably employ rider rollers arranged to be driven at the surface speed of the impression cylinders and to be in contact with the form inking rollers while the forms are being inked, in combination with means for raising the rider rollers automatically out of contact with their form rollers to allow the latter to be rapidly rotated by the distributing rollers when the form rollers are traveling over their distributing rollers at the respective ends.

This may be effected according to one way, by gearing the rider rollers to their respective cylinders through chain or other suitable gearing and mounting the rider rollers in brackets at opposite sides of the cylinder carriage, these brackets being slideable up and down so as to raise and lower the rider rollers and runners or rollers being provided adapted to run up on tapered plates or inclined surfaces located near the ends of the strokes of the cylinder carriage and thereby lift the rider roller brackets so that the rider rollers are clear of the form inking rollers at the ends of the strokes and can be rotated by coming in contact with ink distributing rollers to get a supply of ink.

Further according to the invention I combine with reciprocating and rising and falling cylinders and intermediate sheet transferring mechanism arranged and operating as before described, an arrangement of switches and other suitable mechanism which strip the printed sheet by its leading edge from the perfecting cylinder when the sheet has been released by the grippers of the perfecting cylinder, and an arrangement of automatically rising and falling margin tapes, adapted to hold the sheet down on the perfecting cylinder when it is being carried around by the grippers of this cylinder but to be raised clear of the sheet when this is fed forward from the perfecting cylinder so as not to smear the underneath printed face against the perfecting cylinder in the return stroke.

The invention comprises other improvements which will be seen from the description hereinafter contained.

In a machine according to the invention and arranged for cutting and printing variable sized sheets from a reel, the reel of paper may be mounted in the usual way at the end of the machine and the paper is led through drawing rollers the speed of which can be altered by change wheels to feed more or less paper to the machine per revolution, the paper then passing through between two cutting or perforating cylinders and two breaking cylinders. From the feeding rollers and cutting and breaking cylinders

ders, which may be arranged or operate substantially in the manner described in my British specifications Nos. 23849 of 1912 and 26911 of 1913, the sheets pass or are fed on and the leading edge of the paper passes on to the top or other suitable part of a feed cylinder proper or other feeding device which by means of a set of grippers or the like carries the sheet down and feeds it into the grippers or sheet seizing devices of the first impression cylinder.

In conjunction with or instead of the apparatus above mentioned for cutting and feeding variable sized sheets from a web, means may be employed for feeding previously cut sheets by hand or by an automatic sheet feeding apparatus. An arrangement for both classes of feed may be employed of a character similar to that described in my said British specification No. 26911 of 1913.

As an example of a machine according to the invention the construction may be as follows:—The form beds are arranged in the same plane and placed a suitable distance apart. They are preferably made separate or in two for convenience, but if desired there might be only one form bed in the machine to carry the printing surfaces for both sides of the paper. The two reciprocating cylinders are carried in a suitable carriage, for example between two frames adapted to be moved backward and forward over the forms, and a series of margin tapes or other suitable sheet conveying mechanism is also mounted in the carriage between the cylinders, which are spaced apart and arranged in combination with this sheet conveying mechanism in such manner that the sheet (or the full-sized sheet in the case of variable sized sheets being printed by the machine) after being printed on one side by the first impression cylinder extends from the lower side of this cylinder to about the top of the second impression cylinder.

The carriage is reciprocated by any suitable apparatus, but preferably by connecting rods operated by a crank wheel at each side of the machine.

It is preferred to use crank wheels of half the throw which would be necessary for giving the required stroke to the cylinder carriage, and to double the travel of the cylinder carriage by suitable means, as for example, by providing a rack on the underside of the carriage at each side, and a rack on the frame of the machine at each side, and mounting an axle across under the beds provided with gear wheels of suitable size to engage in the upper and lower racks. The form inking rollers for the respective cylinders will also be arranged to reciprocate or move to and fro with the cylinders.

The two impression cylinders are arranged parallel to one another, and the one cylinder

in its forward stroke prints one side of the sheet, while on the return stroke the other cylinder perfects or prints the sheet on the opposite side. This cylinder passes the perfected sheet on to cylinders or devices for folding the sheet or carrying it to an open delivery. One impression cylinder is raised in each direction of stroke so as to pass over the type without touching it, while the other cylinder is in the lowered printing position as mentioned. The impression cylinders are preferably arranged to make about a revolution and a half during the whole extent of their travel in either direction. Each cylinder carries a set of finger grippers which close on the sheets at the proper time and carry them around for printing in contact with the form. When the carriage or frames carrying the impression cylinders are at say the right hand end of their stroke, the left hand cylinder has its grippers at the top immediately underneath the feed cylinder or device in order to receive the sheet fed to it.

The impression cylinder which has received the sheet starts on its left hand or printing stroke in the reciprocation of the cylinders and prints the sheet on one side. The leading edge of the sheet, immediately after it is printed, enters the margin tapes or other means of conveyance, which carry it from the lower side of the first impression cylinder to near the top side of the second impression cylinder, where it enters grippers or seizing devices of any usual or suitable construction carried by this cylinder. These grippers or devices carry the sheet around on the return stroke of the second cylinder and thus print the paper on the opposite side.

When the second cylinder has made a full revolution or has printed the second side, the grippers carrying the leading edge of the sheet pass under or into co-operative relation with a conveying or folding cylinder carried in bearings on the machine frame. In this case the sheet is transferred to the conveying cylinder or folding cylinder, and as the impression cylinder continues to complete its printing stroke the sheet is carried away out of the printing part of the machine. When the cylinder carriage has completed its right hand stroke the first impression cylinder is again under or in coacting relation with the feeding cylinder or device, which transfers to it another sheet to be printed.

The raising and lowering of the impression cylinders to put them into and out of contact with the printing surfaces may be carried out as follows:—The axles of the impression cylinders are carried in adjustable bushes in eccentric circular disks or bearings, and these circular eccentric disks or 60 bearings are mounted in circular openings

or in any other appropriate manner in the carriage. The bushes carrying the axles are not arranged in the center of the disks but are for example an inch or more at one side of the center, so that when the disk of a cylinder is revolved a few inches, this has the effect of raising or lowering the center of the cylinder axle and putting the cylinder into or out of contact or operative position with the printing surface. 75

On these disks there are arms or projections that come into contact with tappets or levers mounted on the frames or other part of the machine and operated by eccentric devices which act on said levers and thereby through said arms or projections act on the eccentric disks so as to partly revolve same and raise the cylinders out of printing contact during the last inch or so of travel of the cylinders and during the stationary interval 85 at the ends of the stroke and during the first inch or so of travel in the reverse direction.

A tappet or tappets are also provided to act on the disks of the cylinder bushes so as to revolve these back to lower the cylinders 90 into the printing plane at the required times as before mentioned.

Instead of having cylinder raising and depressing tappets or devices at each side of the machine, a cross shaft is preferably arranged to gear both disks together, so that on moving the disk at one side, the shaft and gear wheels move the disk at the opposite end of the cylinder. 95

The impression tappet mechanism is preferably so arranged that it will also form a means of tripping the cylinders, should a sheet be missed, and thus prevent the type from printing on the surface of the impression cylinder. When the cylinders approach the end of the stroke in either direction the mechanism will raise the respective cylinders out of printing contact with the type. Since it is the impression tappet mechanism that puts on the impression, 100 I may provide simple mechanism such that the attendant can put this mechanism out of action and prevent it from putting on the impression to the cylinders. 105

As before mentioned the carriage that carries the reciprocating cylinders preferably also carries the form inking rollers. These rollers are arranged on the left hand side of the left hand impression cylinder and on the right hand side of the right hand cylinder 115 and in order to get good ink distribution, the ink ducts are mounted at the outer ends of the type beds and distributing drums and rollers are carried in the framework of the machine or otherwise arranged so as not to reciprocate with the cylinders, whereas the rollers that apply or put on the ink to the type are carried in the reciprocating carriage of the impression cylinders. The ink rollers on the carriage when traveling 120 125 130

at the end portions of its strokes, travel over the distributing drums at the ends of the type beds and thereby receives supplies of ink as the distributing drums are made to 5 revolve at a good speed, while the ink rollers at the end of the stroke slow down in their reciprocating speeds, rider rollers being driven at the surface speed of the impression cylinders being also provided in 10 combination with the form inking rollers as before mentioned and adapted to be automatically raised out of contact with their form rollers to allow the latter to be rapidly rotated by the distributing rollers when the 15 form rollers are traveling over the distributing rollers.

The accompanying drawings illustrate by way of example a machine constructed to embody the improvements of the invention.

20 Figures 1, 1^a, 1^b, 1^c, 1^d are together a side elevation of the machine.

Fig. 2 is a half cross section on line A—B Fig. 1^a.

25 Fig. 3 is a half cross section on line C, D, Fig. 1^b.

Figs. 4, 5 and 6 are diagrammatic sectional views illustrating the operation of the impression cylinders and sheet transferring mechanism, Fig. 6 also illustrating 30 the transfer of the printed sheet to the conveying cylinder.

Fig. 7 is a detail plan view illustrating the mechanism for operating the impression cylinder grippers.

35 Fig. 8 is a perspective view on a large scale and partly in section illustrating the means for operating the grippers of the impression cylinders.

Fig. 9 is a detail cross section showing in 40 elevation a free wheel mechanism for driving the rollers of the tape mechanism conveying the sheet from one impression cylinder to the other.

Fig. 10 is a detail side elevation on 45 larger scale illustrating the form inking rollers and their rider rollers.

In the example illustrated the machine is provided with mechanism of the kind described in the said British specifications Nos. 50 23859 of 1912 and 26911 of 1913 for cutting variable sized sheets from a web and feeding same to the printing mechanism, and also with means for alternatively feeding sheets by hand or an automatic sheet feeder when so desired.

55 1 is the main frame of the machine on which is mounted at one end a feed board 2 of the usual design for hand fed sheets or suitable for carrying an automatic feeder.

60 Below the feed board is mounted in the main frame mechanism operating as described in the said British specifications Nos. 23859 of 1912 and 26911 of 1913 for cutting and feeding variable sized sheets from a

web 3 drawn from a reel 4 mounted in arms 65 at the feed end of the machine. This mechanism comprises drawing rollers 5, 5^a, 5 being driven by change wheels according to the size of sheet to be cut and fed; perforating rollers 6, 6^a; breaking rollers 7, 7^a, 70 switches 8, 8, 8 and tape runs 9, 9^a arranged to lead the severed sheets to the top of the feeding cylinder 10, the feed table 2 being also arranged so that the leading edge of the sheets fed therefrom passes to the top 75 of cylinder 10.

This cylinder is provided with grippers 11 of known construction operated by a stationary cam 12 on the shaft 13 of cylinder 10 so as to close said grippers on the leading edge of the sheet at the top of the cylinder and carry it around for delivery to the first impression cylinder 14, the grippers being then opened by the cam.

15 is a stop mounted above feeding cylinder 10 for use when the sheets are fed from the feed board. This stop arrests the front end of the sheet and is carried from a pivoted spring controlled arm 16 having a roller 16^a working on a cam 17 on the shaft 90 of cylinder 10, which cam has a step 17^a that allows the stop to drop out of the way to allow the grippers 11 to seize the sheet when they come around to the top of cylinder 10 and carry it away.

When the automatic sheet cutting and feeding mechanism is used, the stop device and arm 16 are swung up and the roller 16^a is then out of contact with cam 17, and the stop device acts as a switch for the automatically fed sheets in a well known way.

18, 18^a are fixed upper and lower guides between which the sheet is led to the grippers 14^a (see Figs. 4 to 6) of the first impression cylinder 14 when it is released by the 105 grippers 11 of cylinder 10. 19 is a pressure roller and 20 a smoothing brush carried on opposite arms 19^a, 20^a of a boss mounted on a stud 22 in the frame 1 and carrying a lever 23 with a roller 23^a working on a cam on the axle of the feeding cylinder 10, the arrangement being such that when the grippers 11 open to release the sheet, the roller 19 feeds the sheet onward until it enters the grippers, whereupon it 115 is swung out of contact with the sheet and by the same movement the smoothing brush is swung on to the sheet.

25 is the second or perfecting impression cylinder.

26, 27 are two type beds for carrying the forms for printing the respective sides of the sheet. These beds are carried in the side frames of the machine and are provided at each end with an inclined plane 28, 29 125 (Figs. 1^a, 1^c) for operating the rider rollers of the form inking mechanism as hereinafter explained.

The impression cylinder 14 and perfecting cylinder 25 together with their inking rollers and the mechanism for conveying the sheet from cylinder 14 to cylinder 25, are 5 mounted in a carriage 30 (see especially Fig. 3) provided at each side with a rack 31; opposite corresponding stationary racks 32 are mounted below them on the side frames, and the carriage 30 is reciprocated 10 by means of toothed wheels 33 keyed on a cross shaft 34 and meshing with the racks 31, 32 at each side, the wheels 33 being coupled by connecting rods 34^a to crank studs 35 of large crank wheels 36 one at each side 15 of the machine. By driving the carriage 30 through fixed stationary racks as explained, the throw of the crank studs 35 is in effect doubled and the carriage is made to travel double the distance traveled by the cross 20 shaft 34.

Racks 37 are provided, one at each side of the machine, running the full length of the type beds, and meshing with toothed wheels on each side of each of the axles of 25 impression cylinders 14 and 25 one of which wheels is seen at 38 in Fig. 3. The cylinders 14 and 25 are arranged to be raised and lowered alternately into and out of printing position as described later, but so that 30 their toothed wheels always remain in gear with the racks 37 at each side.

The grippers 14^a of the first impression cylinder 14 and the grippers 25^a of the second impression cylinder 25 are operated to 35 grip and release the sheet at the required times, and margin tape mechanism arranged and driven as described later is mounted between these cylinders in the carriage so as to convey the sheet from the bottom of the 40 cylinder 14 to the top of cylinder 25.

The grippers of each of these two cylinders are arranged for operation in the manner illustrated in detail with reference to cylinder 14 in Figs. 7 and 8. In these figures 45 39 is the axle of the impression cylinder 14 and 40 the gripper rod (spring seated in the known way) carrying the grippers 14^a. On the axle 39 at the end of the cylinder is mounted a sleeve 41 sliding longitudinally 50 on a key 42 in axle 39. This sleeve has skew teeth at 43. On the end of gripper rod 40 is a toothed segment 44 with skew teeth gearing with those of the sleeve. Thus when the sleeve is slid longitudinally on the 55 axle the skew teeth cause the spring seated gripper rod 40 to oscillate and thereby open and close the grippers. The sliding motion is imparted to the sleeve through the medium of a bell crank lever 45, 45^a hinged in the 60 middle at 46 on a bracket 47 which is attached to the reciprocating carriage 30 in which the impression cylinders are mounted, the arm 45^a of the bell crank lever carrying a roller 48 working in a circumferen-

tial groove 49 of the sleeve 41 and the other 65 arm carrying a roller 50 to be acted upon by cams as explained later.

The construction of the gripper mechanism of the second impression cylinder 25 is the same as that just described of cylinder 70 14, but the upper arm 51 and roller 52 of the bell crank lever 51, 51^a of cylinder 25 do not extend to so high a level as those of cylinder 14, as the grippers of cylinder 25 are operated by different cams than those 75 for cylinder 14.

The action of opening and closing the grippers of cylinders 14 and 25 is illustrated in Figs. 4, 5, 6 and 7.

Fig. 4 shows the sheet being fed to the 80 first impression cylinder 14.

On the axle 13 of the feed-in cylinder 10 is a cam 53. This cam through a roller 54 operates a tappet 55 mounted to swing on an axle 56 attached to the machine frame. 85 This tappet is caused by the cam 53 to swing back, thereby allowing the grippers 14^a of the spring seated gripper bar 40 of cylinder 14 to close on the sheet fed to them from cylinder 10. The carriage 30 with cylinders 90 14 and 25 then moves to the left and when the grippers 14^a have carried the sheet, around so far that its leading edge reaches the entrance of the conveying tapes between the cylinders, the roller 50 of bell crank lever 45, 45^a comes against a fixed bar or cam 57 whereby the grippers are opened to release the sheet. This releasing of the sheet takes place when the roller 50 reaches the point on the cam 57 marked 58, *i. e.* at the 100 top of the beveled end thereof. The grippers 14^a remain open during all the rest of the travel and only close again when their roller 50 passes 58 on their right hand travel.

The advantage of keeping the grippers 105 open all this travel is to prevent noise in closing and opening them again when this is not needed.

When the cylinders 14, 25 are at their farthest travel to the left, the grippers 25^a of cylinder 25 are opened and closed on the sheet fed by the intermediate conveying tapes, by the action of a tappet 59, operated by a cam 60 on shaft 13 of cylinder 10, through the medium of a cam roller 61 carried on a forked lever 62 which embraces by its forked end the axle 13 of cylinder 10 and is connected at the other end to an arm 63 on the axle 64 of the tappet 59, so that 110 this tappet is thus operated by the cam 60. This tappet first opens the spring seated grippers 25^a to receive the sheet, by striking against the roller 52 of their bell crank lever and then springs back under the action of 115 the cam 60 and allows the grippers to close on the sheet (see Fig. 5) and carry it around to print the other side on the return stroke 120 125

of the cylinder carriage. When the sheet has thus been printed on its second side the grippers 25^a are opened (see Fig. 6) by their operating roller 52 coming against another fixed bar cam 65 formed similarly to the bar cam 57 and adapted to hold the grippers 25^a open during the greater part of the travel of the roller 52 on the cam bar 65, the grippers not being closed again until the roller 52 passes the point 66 of cam bar 65 in the left hand stroke of the carriage.

The above describes how the sheet is caught by the grippers 14^a when it is fed to the first cylinder (see Fig. 4) how grippers 14^a are opened to deliver the sheet into the tapes that convey it to the top of the second cylinder 25 (see Fig. 5), how the grippers 25^a of this cylinder are opened and closed upon the sheet (see Fig. 5) and how the grippers 25^a are again opened to release the sheet after it has been printed on both sides (see Figs. 6 and 4).

67 are stripping switches mounted in the carriage 30 near the second impression cylinder 25 and operated by any means commonly employed for actuating such switches, such as a cam loose on the axle of this cylinder and suitably actuated in relation to the grippers and acting through a roller and lever to raise the switches 67 clear of the grippers 25^a when the sheet is being carried by said grippers, and to lower them to position to strip the sheet from the cylinder 25 when it has been carried around and printed thereon and released by the grippers.

The sheets are fed to the grippers 14^a of the first impression cylinder 14 at the moment when the cranks that reciprocate the carriage 30 are at the right hand end of their stroke (Figs. 1^b, 1^c and 4). When the carriage 30 travels to the left, the sheet is carried around by this cylinder and printed on one side as it passes over the form on the left hand type bed 26, the cylinder 14 having been lowered into printing relation with this form and impression cylinder 25 having been raised out of printing relation with the right hand form on type bed 27. At the end of the stroke to the left the cylinder 14 is raised out of printing contact by the mechanism hereinafter described so as to clear the type on form 26 in the return stroke, and in the return stroke the second impression cylinder 25 will be lowered into printing position relatively to the form on bed 27 and will be raised out of printing relation thereto at the end of this stroke, and so on, so that one cylinder is in printing relation to its form in one stroke, and the other in printing relation to its form in the return stroke.

Fig. 5 shows the cylinders 14 and 25 at the farthest point of their left hand stroke. The sheet is shown by the dash line 68, the grippers 25^a having been closed upon the

leading edge by the bell crank lever 51 operated as before described while the stripping switches 67 have been raised as before mentioned to allow the sheet to be carried around by cylinder 25 and printed on the second side when passing over the right hand form 27. It will be seen that the sheet 68 (supposed to be a full sized sheet) reaches from the bottom of cylinder 14 to the top of cylinder 25. 69 represents a set of fixed switches also mounted in the carriage 30 and serving to receive and guide the sheet from the movable stripping switches 67.

Fig. 6 shows the parts during the right hand stroke of the carriage 30 when the right hand cylinder 25 is at about the middle of the right hand form 27. The sheet is seen wrapped around the cylinder 25 and held by the grippers 25^a. The grippers 25^a are just on the point of being opened by the cam bar 65 to release the sheet, and it will be understood that the stripping switches 67 will have been moved close to the cylinder by their operating means to strip the sheet. The further travel and rotation of the cylinder 25 prints the rest of the sheet, the leading edge of which is stripped off the cylinder 25 by the strippers 67 and the sheet is passed along the set of fixed switches 69.

By the time the cylinders have reached the end of their right hand stroke, the leading edge of the sheet has reached the grippers 70 of a folding or conveying cylinder 71 mounted in the side frames of the machine, the grippers 70 being caused by a cam 72 on the cylinder axle to close on the sheet. The fully printed sheet is still partly encircling the second impression cylinder 25, but the further movement of the machine causes cylinder 71 to draw off the sheet 105 while the carriage starts again on its left hand stroke.

The cylinder 71 is provided with a folding blade 73 diametrically opposite its grippers 70, and arranged to fold the sheet into 110 suitably located grippers of a cylinder 74 which carry the partly folded sheet to other folding mechanism of well known form, the first cylinder of which is seen at 75 (Fig. 1^a). For example cylinder 75 may coact 115 with another cylinder to give the sheet a second cross fold. The grippers of cylinder 74 are not shown but they may be of any suitable form and operated in any convenient way.

If the sheets are not required to be folded and are to be delivered flat, the folding blade of cylinder 71 may be removed or dispensed with, and the cylinder 71 can transfer the sheet to an intermediate cylinder 76 having grippers to receive it and which passes it on along an apron of tapes 77 to a well known open delivery mechanism comprising cylinders 78, 79 having sprocket chains 80 passing around them carrying trav- 130

eling grippers 81 which seize the sheets, carry them along over the delivery board 82 and deposit them in the well known way between joggers 83 operated by the usual mechanism.

Either the folding arrangement or the open delivery arrangement may be employed as desired or the machine may comprise only one of these arrangements.

84, Fig. 1^c, represents a set of non-traveling margin tapes or wires passing around rollers 85, 86 carried on the arms 87, 87^a of a lever pivoted at 88 to the side frame of the machine, these tapes or wires being kept 15 taut by springs 89 interposed in their length. These tapes or wires serve to hold the sheet down on top of the perfecting cylinder 25 when it is seized and carried around by the grippers 25^a, but as the sheet comes around 20 to the top in the rotation of this cylinder and is fed forward to the conveying cylinder 71, it is necessary to raise the margin tapes or wires 84 to prevent smudging of the printed under face by rubbing against 25 the cylinder 25 on the return stroke of this cylinder. For this purpose the arm 87^a of the pivoted lever carries at its end a cam roller 90 working against a cam 91 on the axle of cylinder 71, this cam being adapted 30 to rock the lever 87, 87^a and thereby automatically swing the tapes or wires 84 down or allow them to rise so as to lower them into contact with the cylinder 25 at the required times.

35 An important feature of the invention is the mechanism for conveying the partly printed sheet from cylinder 14 to the grippers 25^a of cylinder 25 or allow them to rise out of contact therewith. It is necessary that no rub shall take place on the under and newly printed side of the sheet, as this would smear the print. For this purpose the tapes 92, 93 that convey the sheet from cylinder 14 to the top of cylinder 25 to be seized by the grippers 25^a are made to travel always at the surface speed of the cylinders but always in one direction, while the cylinders travel in the opposite directions alternately. One suitable form

50 of mechanism for effecting this continuously forward motion of the tapes while the cylinders have a reciprocating motion is shown in the drawings. In this arrangement (see Figs. 1^b, 1^c) an upper run of guiding tapes 92 passes around the tape rollers 94, and 95, and margin tapes 96 pass around the cylinder 14 and the roller 94 between the guiding tapes 92 of the upper run from 94 to 95, the set of margin tapes 96 thus going around 55 the cylinder 14 and the roller 94, and the upper set of tapes 92 running between rollers 94 and 95. The lower run of tapes 93 passes around tape rollers 98, 98 at each end, and an intermediate driven roller 99 60 geared to roller 94 and arranged to be driven

by a species of free wheel mechanism as follows.

100 is a gear wheel carried by a stud 101 (Fig. 9) in the carriage 30. This wheel 100 meshes in the toothed rack 37 on the frame at one side of the type beds and also with a loose wheel 102 mounted on the axle 99^a of tape roller 99. Keyed on the axle 99^a is a ratchet wheel 103. Mounted on the face of the loose gear wheel 102 is a pawl 104. Gear wheel 100 has fastened to the side of it another gear wheel 105 which drives another stud wheel 106 and through this a wheel 107 mounted loose on the axle 99^a of roller 99, this wheel 107 carrying a pawl 108 lying on the other side of the ratchet wheel 103 from pawl 104. As will be seen, the two loose wheels 102 and 107 run in opposite directions. As the pawl 104 or 108 carried by each will only engage and drive 85 the ratchet wheel 103 in one direction of their motion it follows that this combination of mechanism will drive roller 99 always in one direction (the forward direction) whichever way the carriage 30 travels 90 with the impression cylinders.

I have shown ratchet and pawls as a suitable means of converting the backward and forward motion into a continuously forward movement, but there are many equivalent 95 devices which could be used for the purpose.

As before mentioned the impression cylinders 14 and 25 are raised and lowered alternately to put the impression on and off them for their respective printing strokes and idle 100 strokes. This is effected as follows:—The axles of the cylinders 14 and 25 are carried in conical adjustable bushes 109 (Fig. 3) held in eccentric disks or bearings 110 mounted in circular openings in the side 105 frames of the carriage and arranged to be partially rotated as about to be explained, and when thus rotated the cylinders are slightly raised above the level of the form so that they can pass over in one direction 110 without touching the form, but only to such an extent that the gear wheels of the respective cylinders 14, 25 still remain in gear with the racks 37 on the frame.

At one side of the machine the eccentric 115 bearings 110 are formed with lugs 111 carrying cam rollers 112 and also with teeth at one part of their periphery as at 113, these teeth gearing with pinions 114 on cross axles 115 carried in the carriage 30 near each cylinder 14 and 25 and serving to carry the motion of the eccentric bearings at one side of the machine across the machine to the eccentric bearings at the other end of the cylinders which likewise have teeth meshing 120 with corresponding toothed wheels on the cross axles 115 at that side.

116, 117 are rocking spring-controlled tappets mounted on studs 118, 119 in the frame at the respective ends of the machine at the 130

same side as the eccentric bearings formed with the lugs 111, these tappets being operated respectively by eccentric cams 120, 121 mounted respectively on the stud shaft 122 and the axle 123 of the folding or conveying cylinder 71, these cams acting on the tappets through cam rollers 124, 125 carried by the tappets.

When the carriage 30 nearly reaches either 10 end of its stroke, the roller 112 of the eccentric bearing of the cylinder at that end passes on to the corresponding tappet 116 or 117. These tappets are so timed by their operating cams 120, 121 that when the carriage is nearing the corresponding end of its travel they lift the roller 112 of the given cylinder and thereby partly rotate the eccentric bearings and raise the cylinder out of printing relation to the type.

20 There is of course a period at the end of the travel of the carriage, just before and after the driving cranks 35 of wheels 36 pass the dead center, when the travel of the carriage is very slow. The cams 120, 121 and 25 tappets 116, 117 are so timed that while the carriage 30 travels about the last inch one way, and while it is stationary and also during about its first inch of travel in the reverse way, they perform their work of raising the cylinders without shock or jar.

Each cylinder is thus raised off the impression so as to return over the type without contact, notwithstanding that the gear wheels 38, on the cylinder axles 39 remain in 35 mesh with the racks 37 and rotate the cylinders in the alternate directions.

The impression cylinders 14 and 25 make about a revolution and a half in each stroke of the carriage.

40 Before the cylinders 14 and 25 reach their respective forms in their printing strokes the impression has to be put on the cylinder which is to print in the given stroke. This is done by means of a rising and falling tappet member 126 having slots 127 and guide faces 128 working on rollers 129 carried by studs 130 mounted in the side frame, and also a rack 131 meshing with a toothed segment 132 pivoted on a stud 133 on the frame 45 and having a tail 134 on its boss connected to the side frame by a spring 135, the tappet plate 126 being connected to a bell crank lever 136, pivoted at 137 and having a cam roller 138 working on a cam 139 on the axle 50 13 of cylinder 10. The tappet plate 126 is caused by the cam 139 and lever 136 working against the action of the spring 135, to rise and fall at the required times to clear or act upon the rollers 112 of the eccentric 55 bearings of the printing cylinders 14, 25.

When the roller 112 of the respective cylinder (previously raised by the corresponding tappet 116 or 117 as before mentioned) strikes the tappet plate 126 which is lowered

at the required times by the cam 139, the eccentric bearing of this cylinder is turned down again to bring the cylinder into printing relation with the form, the tappet plate 126 always acting at the required time to put the impression on the respective cylinders. 70

140, 140, Figs. 1^b and 1^c represent notches formed in the eccentric disks 110 of cylinders 14, 25, and adapted to engage the noses of spring pressed catch levers 141, when these disks are turned by tappet plate 126 75 to lower the cylinders 14, 25 to printing level, and thereby retain the latter in the printing position.

Referring to the inking apparatus, the set of inking mechanism for each cylinder 80 14 and 25 is arranged on the outer side of the corresponding impression cylinder and each set comprises inking rollers mounted on the carriage and distributing rollers carried by the frame at the respective 85 ends and serving to distribute the ink to the inking rollers.

In each set, (see more particularly Figs. 10 and 1^b) 142, 142, 142, are composition form inking rollers and 143, 143 are steel 90 rider rollers resting on the inking rollers 142 for the purpose of giving extra distribution of the ink and also for driving the inking rollers at the surface speed at which they are to rotate when passing over their respective forms. These inking rollers and rider rollers are mounted on the carriage 30 in the outer sides of their corresponding cylinders and the rider rollers 143 of each set are driven by a stud gear wheel 144 100 mounted between them and driven by a pitch chain 145 from a wheel on the end of the corresponding cylinder 14 and 25.

146, 146, 146, 146 are sets of distributing steel rollers mounted in the frames at the 105 respective ends of the machine and receiving ink from ducts 147, 147 of usual construction, these distributing rollers being in contact with intermediate ink conveying rollers 148, 148, 148 and being driven at a considerable and constant speed imparted to the set at the left hand end of the machine by a gear wheel 149 and to the set at the right hand end by a gear-wheel 150, the wheels 149 and 150 each meshing with a pinion on the end roller 148 and the ink conveying rollers being geared to the distributing rollers 146 by toothed pinions 151 as indicated.

When the form inking rollers 142 of each 120 set are passing over the type of their form, the rider rollers 143 are resting on them and driving them at the required speed for inking the form. At the end portions of the strokes of the carriage 30 the form rollers 142 at the given end pass over the steel distributing rollers 146 and while the form rollers are passing slowly over these 125

rollers in this portion of the motion of the carriage, the distributing rollers 146 running at a considerable and constant speed as mentioned, distribute ink to the form 5 rollers for inking the form for the next sheet to be printed.

The ink is supplied from the ducts 147 to the distributing rollers 146 in any usual manner such as shown in which a cam 152 10 on the axle 153 of wheel 149, and a similar cam 154 on the axle 155 of wheel 150, respectively operate vibrating messenger or ductor rollers 156, 156 through bell crank levers 157, 157, and the ink duct advancing 15 movement is imparted by rods 158, 158 which may also be operated by the cams 152, 154 or otherwise; the intermediate conveying rollers 148 can also be operated with an endwise or so called "waving motion" by 20 cams on the axles 153, 155 or otherwise in the well known way.

When the composition form rollers 142 are in contact with the type the rider rollers 143 are closed down upon them and driving 25 them. When the form rollers 142 are passing over the distributing rollers 146 the rider rollers 143 are raised off the form rollers 142 so as to allow these to be freely revolved by contact with the distributing 30 rollers. For this purpose the rider rollers 143 are carried in bearing brackets 159, 160 at opposite sides of the carriage 30. These brackets are slidable up and down so as to raise or lower the rider rollers. At all 35 times except at the ends of the stroke the rider rollers 143 rest on the form inking rollers 142. When, however, the carriage 30 nearly reaches the end of its stroke in the respective directions, runners or rollers 161, 40 162 run on to the inclined planes 28, 29 before referred to. This causes the runners 161, 162 to lift the roller brackets so that the rider rollers 143 are clear of the form inking rollers 142 so that these latter can be 45 rotated by coming in contact with the distributing rollers and thus get a supply of ink.

The manner of driving the machine will be apparent. 170 is the main driving shaft 50 which may receive the power from any prime mover or belt. On this shaft is a toothed wheel 171 at each side of the machine, these toothed wheels gearing with the crank wheels 36 (one at each side). On 55 the front side of the machine a gear wheel 172 is mounted on the axle 36^a of the crank wheels behind the front crank wheel. This wheel 172 drives the stud wheel 173 which conveys power to the gear wheel 174. This 60 wheel is mounted on the cross axle 122 that carries the cam 120 and it drives the stud gear wheels 175, 176, 177 conveying power to the web cutting and feeding mechanism, the wheel 177 gearing with a wheel 178

which meshes with pinions 179, 180 on the 65 axles of cylinders 6 and 7, and the lower drawing roller 5 being driven through change gear.

The wheel 172 also drives a stud wheel 181 which is sufficiently broad to gear into both 70 wheels 172 and 149 which latter drives the composition inking rollers 148 and steel ink rollers 146 at the left hand end of the machine.

The wheel 36 drives the wheel 182 and 75 axle 183 which in turn drive the side shaft 184 by a pair of miter wheels 185, 186. The power to drive the conveying cylinder 71, folding mechanism and feed in cylinder 10 is conveyed from the side shaft 184 by the 80 upright shaft 187 to a cross shaft 188 by bevel gears 189, 190. The gear wheel 191 on cross shaft 188 drives the conveying cylinder 71 by a gear wheel 192 on the axle of this cylinder and which in turn drives cylinders 74, 75. The gear wheel 191 also drives the stud wheels 193, 194, 195, the last of which meshes with a gear wheel 196 on the axle 13 of the feed in cylinder 10.

The stationary inking mechanism at the 90 right hand end of the machine, and which as before mentioned is the same as that at the left hand end, is driven by bevel gear 197, 198 and a toothed wheel 199 which meshes with the wheel 150 that drives the 95 ink rollers 148.

The operation of the machine above described is substantially as follows. The sheets being cut from the web 3 by the feeding, perforating and breaking cylinder 5, 100 5^a, 6, 6^a, 7, 7^a or being fed from the feed board 2 as explained pass to the feed cylinder 10. This carries the sheets into the grip of the grippers 14^a of the first impression cylinder 14 when this is at the end of its 105 right hand stroke, and this cylinder 14 in moving to the left prints the paper on one side. Just after the tail end of the sheet has left the type of the left hand form (when doing a full sized sheet) the leading edge 110 of the sheet has reached the grippers 25^a on top of the second impression cylinder 25. The crank mechanism for reciprocating the cylinders brings the carriage and cylinders and sheet to a standstill just at the moment 115 the sheet reaches the grippers 25^a of the second cylinder and these close on it. The grippers 25^a carry the sheet around and print the other side on the right hand form in the return stroke of the carriage; the 120 grippers 25^a then open and the switches 67 and 69 strip the sheet from the cylinder 25 and pass it on to the folding or conveying cylinder 71, which may act to give the sheet a cross fold in conjunction with another 125 folding cylinder or to forward it to the open delivery as described.

F, Fig. 3 indicates diagrammatically a

foot board which can be used when the hand feed is employed, and S in the same figure indicates a stay to support the upper frame of the machine.

5 It is to be understood that the machine described in detail with reference to the drawings is only given by way of example and that modifications may be made within the spirit of the invention.

10 What I claim and desire to secure by Letters Patent is:—

1. A flat bed printing and perfecting machine comprising in combination two impression cylinders and type beds therefor, 15 means for reciprocating said cylinders together over the type beds, means for imparting rotation to said cylinders both in one direction in one stroke of the cylinders and both in the opposite direction in the next 20 stroke of the cylinders in the reciprocation, means for alternately and inversely lowering and raising said cylinders into and out of printing relation with the type beds, means located between and reciprocating 25 with the cylinders for conveying the sheet printed on one side from the lower part of the first impression cylinder to about the top of the second impression cylinder, grippers on the second impression cylinder adapted 30 to seize the leading end of the sheet so fed by said conveying means, and means for opening said grippers to release the sheet after it has been carried around and printed by the second impression cylinder.

35 2. A flat bed printing and perfecting machine comprising in combination two impression cylinders and type beds therefor, means for reciprocating said cylinders together over the type beds, racks for imparting rotation to said cylinders, both in one direction in one stroke of the cylinders and both in the opposite direction in the next stroke of the cylinders in the reciprocation, means for alternately and inversely lowering 40 and raising said cylinders into and out of printing relation with the type beds, means located between and reciprocating with the cylinders for conveying the sheet printed on one side from the lower part of the first impression cylinder to about the top of the second impression cylinder, grippers on the second impression cylinder adapted to seize the leading end of the sheet so fed by said conveying means, and means for opening 45 said grippers to release the sheet after it has been carried around and printed by the second impression cylinder, the spacing of the impression cylinders being such that a full sized sheet, after printing on one side 50 by the first impression cylinder reaches from the lower side thereof to about the top of the second impression cylinder, substantially as described.

55 3. A flat bed printing and perfecting machine comprising in combination two im-

pression cylinders and type beds therefor, means for reciprocating said cylinders together over the type beds, racks for imparting rotation to said cylinders both in one direction in one stroke of the cylinders and 70 both in the opposite direction in the next stroke of the cylinders in the reciprocation, means for alternately and inversely lowering and raising said cylinders into and out of printing relation with the type beds, conveying tapes located between and reciprocating with the cylinders, for conveying the sheet printed on one side from the lower part of the first impression cylinder to about the top of the second impression cylinder, grippers on the second impression cylinder adapted to seize the leading edge of the sheet so fed by said conveying tapes, and means for opening said grippers to release the sheet after it has been carried around and printed 80 by the second impression cylinder.

4. A flat bed printing and perfecting machine comprising in combination two impression cylinders and type beds therefor, means for reciprocating said cylinders together over the type beds, racks for imparting rotation to said cylinders both in one direction in one stroke of the cylinders and both in the opposite direction in the next stroke of the cylinders in the reciprocation, 90 means for alternately and inversely lowering and raising said cylinders into and out of printing relation with the type beds, conveying tapes located between and reciprocating with the cylinders, for conveying the sheet printed on one side from the lower part of the first impression cylinder to about the top of the second impression cylinder, grippers on the second impression cylinder adapted to seize the leading edge of the sheet so fed by said conveying tapes, and means for opening said grippers to release the sheet after it has been carried around and printed 95 by the second impression cylinder.

100 5. A flat bed printing and perfecting machine comprising in combination two impression cylinders and type beds therefor, means for reciprocating said cylinders together over the type beds, racks for imparting rotation to said cylinders both in one direction in one stroke of the cylinders and both in the opposite direction in the next stroke of the cylinders in the reciprocation, means for alternately and inversely lowering and raising said cylinders into and out of printing relation with the type beds, conveying tapes located between and reciprocating with the cylinders, for conveying the sheet printed on one side from the lower part of the first impression cylinder to about the top of the second impression cylinder, grippers on the second impression cylinder adapted to seize the leading edge of the sheet so fed by said conveying tapes, and means for opening said grippers to release the sheet after it has been carried around and printed 105 by the second impression cylinder, grippers on the first impression cylinder to grip and carry around the sheet on the first impression cylinder, and means for operating the grippers of the first impression cylinder to close and grip the sheet and to release the sheet to the said conveying tapes leading to the upper part of the second impression cylinder, substantially as described.

110 6. A flat bed printing and perfecting machine comprising in combination two impression cylinders and type beds therefor, means for reciprocating said cylinders together over the type beds, racks for imparting rotation to said cylinders both in one direction in one stroke of the cylinders and both in the opposite direction in the next stroke of the cylinders in the reciprocation, means for alternately and inversely lowering and raising said cylinders into and out of printing relation with the type beds, conveying tapes located between and reciprocating with the cylinders, for conveying the sheet printed on one side from the lower part of the first impression cylinder to about the top of the second impression cylinder, grippers on the second impression cylinder adapted to seize the leading edge of the sheet so fed by said conveying tapes, and means for opening said grippers to release the sheet after it has been carried around and printed 115 by the second impression cylinder, grippers on the first impression cylinder to grip and carry around the sheet on the first impression cylinder, and means for operating the grippers of the first impression cylinder to close and grip the sheet and to release the sheet to the said conveying tapes leading to the upper part of the second impression cylinder, substantially as described.

120 7. A flat bed printing and perfecting machine comprising in combination two impression cylinders and type beds therefor, means for reciprocating said cylinders together over the type beds, racks for imparting rotation to said cylinders both in one direction in one stroke of the cylinders and both in the opposite direction in the next stroke of the cylinders in the reciprocation, means for alternately and inversely lowering and raising said cylinders into and out of printing relation with the type beds, conveying tapes located between and reciprocating with the cylinders, for conveying the sheet printed on one side from the lower part of the first impression cylinder to about the top of the second impression cylinder, grippers on the second impression cylinder adapted to seize the leading edge of the sheet so fed by said conveying tapes, and means for opening said grippers to release the sheet after it has been carried around and printed 125 by the second impression cylinder, grippers on the first impression cylinder to grip and carry around the sheet on the first impression cylinder, and means for operating the grippers of the first impression cylinder to close and grip the sheet and to release the sheet to the said conveying tapes leading to the upper part of the second impression cylinder, substantially as described.

- rocating with the cylinders, for conveying the sheet printed on one side from the lower part of the first impression cylinder to about the top of the second impression cylinder, 5 grippers on the second impression cylinder adapted to seize the leading edge of the sheet so fed by said conveying tapes, means for opening said grippers to release the sheet after it has been carried around and 10 printed by the second impression cylinder, grippers on the first impression cylinder to grip and carry around the sheet on the first impression cylinder, and means for operating the grippers of the first impression cylinder to close and grip the sheet and to release the sheet to the said conveying tapes leading to the upper part of the second impression cylinder, the spacing of the impression cylinders being such that a full 15 sized sheet, after printing on one side by the first impression cylinder, reaches from the lower side thereof to about the top of the second impression cylinder, substantially as described.
- 20 6. A flat bed printing and perfecting machine comprising in combination two impression cylinders and type beds therefor, means for reciprocating said cylinders together over the type bed racks for imparting rotation to said cylinders both in one direction in one stroke of the cylinders and both in the opposite direction in the next stroke of the cylinders in the reciprocation, eccentric bearings in which the impression 25 cylinders are mounted, devices for operating said eccentric bearings alternately, to raise the cylinders and adapted to partly revolve said bearings and thereby raise the cylinders during the last inch or so of the reciprocating travel of the cylinders and during the 30 stationary interval at the ends of the stroke and during the first inch or so of travel in the reverse direction, means for conveying the sheet printed on one side from the lower part of the first impression cylinder to about the top of the second impression cylinder, grippers on the second impression cylinder adapted to seize the leading edge of the sheet so fed by said conveying tapes, means for opening said grippers to release the sheet after it has been carried around and printed by the second impression cylinder, substantially as described.
- 35 7. A flat bed printing and perfecting machine comprising in combination two impression cylinders and type beds therefor, means for reciprocating said cylinders together over the type bed racks for imparting rotation to said cylinders both in one direction in one stroke of the cylinders and both in the opposite direction in the next stroke of the cylinders in the reciprocation, eccentric bearings in which the said impression 40 cylinders are mounted and having arms for turning them, levers for acting on said arms, devices for acting on said levers alternately, to partly revolve said bearings and thereby raise the cylinders during the concluding portion of the reciprocating travel and during the stationary interval between the strokes and during the initial portion of the travel in the reverse direction, means located between and reciprocating with the cylinders for conveying the sheet printed on one side from the lower part of the first cylinder to about the top of the second cylinder, grippers on the second cylinder adapted to seize the leading edge of the sheet so fed by said conveying tapes, means for opening said grippers to release the sheet after it has been carried around and printed by the second cylinder, and tappet mechanism located intermediately of the travel of the cylinders to act on the eccentric bearings in the reciprocation and thereby lower the cylinders to the printing plane, substantially as described.
- 45 8. A flat bed printing and perfecting machine comprising in combination two impression cylinders and type beds therefor, means for reciprocating said cylinders together over the type bed racks for imparting rotation to said cylinders both in one direction in one stroke of the cylinders and both in the opposite direction in the next stroke of the cylinders in the reciprocation, eccentric bearings in which the said impression 50 cylinders are mounted and having arms for turning them, levers for acting on said arms, devices for acting on said levers alternately, to partly revolve said bearings and thereby raise the cylinders during the concluding portion of the reciprocating travel and during the stationary interval between the strokes and during the initial portion of the travel in the reverse direction, means located between and reciprocating with the cylinders for conveying the sheet printed on one side from the lower part of the first cylinder to about the top of the second cylinder, grippers on the second cylinder adapted to seize the leading edge of the sheet so fed by said conveying tapes, means for opening said grippers to release the sheet after it has been carried around and printed by the second cylinder, and tappet mechanism located intermediately of the travel of the cylinders to act on the eccentric bearings in the reciprocation and thereby lower the cylinders to the printing plane, substantially as described.
- 55 9. A flat bed printing and perfecting machine comprising in combination two impression cylinders and type beds therefor, means for reciprocating said cylinders together over the type bed racks for imparting rotation to said cylinders both in one direction in one stroke of the cylinders and both in the opposite direction in the next stroke of the cylinders in the reciprocation, eccentric bearings in which the said impression 60 cylinders are mounted and having arms for turning them, levers for acting on said arms, devices for acting on said levers alternately, to partly revolve said bearings and thereby raise the cylinders during the concluding portion of the reciprocating travel and during the stationary interval between the strokes and during the initial portion of the travel in the reverse direction, means located between and reciprocating with the cylinders for conveying the sheet printed on one side from the lower part of the first cylinder to about the top of the second cylinder, grippers on the second cylinder adapted to seize the leading edge of the sheet so fed by said conveying tapes, means for opening said grippers to release the sheet after it has been carried around and printed by the second cylinder, and tappet mechanism located intermediately of the travel of the cylinders to act on the eccentric bearings in the reciprocation and thereby lower the cylinders to the printing plane, substantially as described.
- 65 10. A flat bed printing and perfecting machine comprising in combination two impression cylinders and type beds therefor, means for reciprocating said cylinders together over the type bed racks for imparting rotation to said cylinders both in one direction in one stroke of the cylinders and both in the opposite direction in the next stroke of the cylinders in the reciprocation, eccentric bearings in which the said impression cylinders are mounted and having arms for turning them, levers for acting on said arms, devices for acting on said levers alternately, to partly revolve said bearings and thereby raise the cylinders during the concluding portion of the reciprocating travel and during the stationary interval between the strokes and during the initial portion of the travel in the reverse direction, means located between and reciprocating with the cylinders for conveying the sheet printed on one side from the lower part of the first cylinder to about the top of the second cylinder, grippers on the second cylinder adapted to seize the leading edge of the sheet so fed by said conveying tapes, means for opening said grippers to release the sheet after it has been carried around and printed by the second cylinder, and tappet mechanism located intermediately of the travel of the cylinders to act on the eccentric bearings in the reciprocation and thereby lower the cylinders to the printing plane, substantially as described.

5 during the concluding portion of the reciprocating travel and during the stationary interval between the strokes and during the initial portion of the travel in the reverse direction, tappet mechanism located intermediately of the travel of the cylinders, to act on the eccentric bearings in the reciprocation and thereby lower the cylinders to the printing plane, means located between 10 and reciprocating with the cylinders for conveying the sheet printed on one side from the lower part of the first cylinder to about the top of the second cylinder, gripping devices on the second cylinder for seizing the 15 sheet so fed by said conveying means, and means for operating said gripping devices to release the sheet after it has been carried around and printed by the second cylinder, the spacing of the said cylinders being such 20 that a full sized sheet, after printing on one side by the first cylinder, reaches from the lower side thereof to about the top of the second cylinder, substantially as described.

10. A flat bed printing and perfecting machine comprising in combination two impression cylinders and type beds therefor, means for reciprocating said cylinders together over the type beds, racks for imparting rotation to said cylinders both in one direction in one stroke of the cylinders and both in the opposite direction in the next stroke of the cylinders, in the reciprocation, means for alternately and inversely lowering and raising said cylinders into and out of 30 printing relation with the type beds, roller-driven sheet conveying means located between and reciprocating with the cylinders for conveying the sheet printed on one side from the lower part of the first impression 35 cylinder to about the top of the second impression cylinder, means for revolving the rollers of said sheet conveying means in a constant direction at the surface speed of the impression cylinders while these cylinders 40 revolve in alternate directions, gripping devices on the second impression cylinder for seizing the leading edge of the sheet so fed by said conveying means, and means for operating said gripping devices to release 45 the sheet after it has been carried around and printed by the second impression cylinder.

11. A flat bed printing and perfecting machine comprising in combination two impression cylinders and type beds therefor, 50 means for reciprocating said cylinders together over the type beds, racks for imparting rotation to said cylinders both in one direction in one stroke of the cylinders and both in the opposite direction in the next 55 stroke of the cylinders, in the reciprocation, means for alternately and inversely lowering and raising said cylinders into and out of printing relation with the type beds, roller-driven sheet conveying tapes located 60 between and reciprocating with the cylinders 65

ders for conveying the sheet printed on one side from the lower part of the first impression cylinder to about the top of the second impression cylinder, means for revolving the rollers of said sheet conveying 70 tapes in a constant direction at the surface speed of the impression cylinders while these cylinders revolve in alternate directions, gripping devices on the second impression cylinder for seizing the leading 75 edge of the sheet so fed by said conveying means, and means for operating said gripping devices to release the sheet after it has been carried around and printed by the second impression cylinder. 80

12. A flat bed printing and perfecting machine comprising in combination two impression cylinders and type beds therefor, means for reciprocating said cylinders together over the type beds, racks for imparting rotation to said cylinders both in one direction in one stroke of the cylinders and both in the opposite direction in the next stroke of the cylinders, in the reciprocation, means for alternately and inversely lowering and raising said cylinders into and out of printing relation with the type beds, roller-driven sheet conveying means located between and reciprocating with the cylinders for conveying the sheet printed on one side from the lower part of the first impression cylinder to about the top of the second impression cylinder, free wheel mechanism adapted to transmit the reciprocating motion of the cylinders as a drive means to the sheet conveying mechanism in a constant direction while the cylinders revolve in alternate directions, gripping devices on the second impression cylinder for seizing the leading edge of the sheet so fed by said conveying means, and means for operating said gripping devices to release the sheet after it has been carried around and printed by the second impression cylinder. 85 90 95 100 105

13. A flat bed printing and perfecting machine comprising in combination two impression cylinders and type beds therefor, means for reciprocating said cylinders together over the type beds, racks for imparting rotation to said cylinders both in one direction in one stroke of the cylinders and both in the opposite direction in the next stroke of the cylinders in the reciprocation, means for alternately and inversely lowering and raising said cylinders into and out of printing relation with the type beds, roller-driven sheet conveying means located between and reciprocating with the cylinders for conveying the sheet printed on one side from the lower part of the first impression cylinder to about the top of the second impression cylinder, free wheel mechanism comprising a ratchet wheel and oppositely driven pawls, adapted to transmit the reciprocating motion of the cylinders as a drive 130

- means to the sheet conveying mechanism in a constant direction while the cylinders revolve in alternate directions, gripping devices on the second impression cylinder for seizing the leading edge of the sheet so fed by said conveying means, and means for operating said gripping devices to release the sheet after it has been carried around and printed by the second impression cylinder.

14. A flat bed printing and perfecting machine comprising in combination two impression cylinders and type beds therefor, means for reciprocating said cylinders together over the type beds, means for imparting rotation to said cylinders both in one direction in one stroke of the cylinders and both in the opposite direction in the next stroke of the cylinders, in the reciprocation, means for alternately and inversely lowering and raising said cylinders into and out of printing relation with the type beds, sheet conveying means located between and reciprocating with the cylinders for conveying the sheet printed on one side from the lower part of the first impression cylinder to about the top of the second impression cylinder, gripping devices on the second impression cylinder and means for operating same to seize the sheet so fed by said conveying means and to release the sheet after it has been carried around and printed by the second impression cylinder, means for stripping the printed sheet by its leading edge from the perfecting cylinder, tapes or wires adapted to hold the sheet down on the perfecting cylinder when it is being carried around by the gripping devices thereof, and means for automatically lowering said tapes or wires on to the cylinder and raising said tapes or wires clear of the printed surface when the perfecting cylinder starts on its back stroke so as to free the sheet and not smear the print, substantially as described.

15. A flat bed printing and perfecting machine comprising in combination two impression cylinders and type beds therefor, means for reciprocating said cylinders together over the type beds, means for imparting rotation to said cylinders both in one direction in one stroke of the cylinders and both in the opposite direction in the next stroke of the cylinders, in the reciprocation, means for alternately and inversely lowering and raising said cylinders into and out of printing relation with the type beds, spring grippers on said cylinders for seizing and releasing the sheet at the required times, sheet conveying means located between and reciprocating with the cylinders for conveying the sheet printed on one side from the lower part of the first impression cylinder to the grippers of the second impression cylinder, at about the top of this cylinder, sliding members on the impression cylinders adapted to open the grippers of the impression cylinders by their sliding motion, tappet levers reciprocating with said cylinders for sliding said sliding members, cam actuated tappet mechanism adapted to act on said tappet levers for opening the grippers of the impression cylinders to receive the sheet at the required times respectively and then allowing them to close thereon, and fixed cams located to act on said tappet levers in the reciprocation thereof, to open the grippers to release the sheet and adapted to hold the grippers open in the end portions and for a considerable part of the reciprocating travel, substantially as and for the purpose described.

16. A flat bed printing and perfecting machine comprising in combination two impression cylinders and type beds therefor, means for reciprocating said cylinders together over the type beds, means for imparting rotation to said cylinders both in one direction in one stroke of the cylinders and both in the opposite direction in the next stroke of the cylinders, in the reciprocation, means for alternately and inversely lowering and raising said cylinders into and out of printing relation with the type beds, spring grippers on said cylinders for seizing and releasing the sheet at the required times, sheet conveying means located between and reciprocating with the cylinders for conveying the sheet printed on one side from the lower part of the first impression cylinder to the grippers of the second impression cylinder, at about the top of this cylinder, sliding members on the impression cylinders adapted to open the grippers of the impression cylinders by their sliding motion, tappet levers reciprocating with said cylinders for sliding said sliding members, cam actuated tappet mechanism adapted to act on said tappet levers for opening the grippers of the impression cylinders to receive the sheet at the required times respectively and then allowing them to close thereon, and fixed cams located to act on said tappet levers in the reciprocation thereof, to open the grippers to release the sheet and adapted to hold the grippers open in the end portions and for a considerable part of the reciprocating travel, substantially as and for the purpose described.

In witness whereof, I have hereunto signed my name in the presence of two subscribing witnesses.

ROBERT CUMMING ANNAND.

Witnesses:

ELIZA HOLMES BARCLAY,
JAMES COULSON THOMAS.
